UNITED STATES PATENT OFFICE.

HOWARD FREDERIC CHISM, OF OLIVE BRANCH, ILLINOIS.

SELF-RESERVING TABLET.

1,155,886.

Patented Oct. 5, 1915.

Application filed June 3, 1914. Serial No. 842,630.

To all whom it may concern:

Be it known that I, HOWARD F. CHISM, a citizen of the United States, residing at Olive Branch, in the county of Alexander and State of Illinois, have invented certain new and useful Improvements in Self-Reserving Tablets, of which the following is a specification.

This invention relates to self-reserving writing tablets, and one of the principal objects of the invention is to provide a tablet for use with either a pen, pencil, stylus or for typewritten matter, in which provision is made for detachment and for connecting the carbon or second sheet in the book in its proper place after it has been written upon or typewritten.

Another object of the invention is to provide a convenient writing tablet which will preserve copies of each sheet detached and which may be used as a letter file for future reference.

These and other objects may be attained by means of the construction illustrated in the accompanying drawing, in which,

Figure 1 is a front elevation of a writing tablet made in accordance with this invention and showing the cover thrown backward in position to permit the tablet to be used as a writing tablet, Fig. 2 is a sectional view taken on the line 2—2 of Fig. 1, the leaves being broken away at their ends and only a few of the leaves being shown, Fig. 3 is an edge view of one of the sheets and a stub and a sheet for the carbon copy underneath the same, Fig. 4 is a sectional view showing the two first sheets of the book removed on one of the scored lines for typewriting, Fig. 5 is an edge view of one of the carbon copy sheets connected to the stub, Fig. 6 is a fragmentary perspective view on a larger scale of the upper end of one of the stubs and a carbon sheet connected underneath the original or primary sheet, Fig. 7 is a detail showing the clip for securing the leaves of the book in place and for holding the carbon paper therein, and Fig. 8 is a perspective view of the clip removed from the book.

Referring to the drawing, the numeral 1 designates the top cover of the book, and 2 is the binding strip which passes around the top or back of the book or tablet for holding the leaves in place.

Each sheet of the tablet comprises a primary sheet *a* for the original letter or memo-

randa, and connected integrally with the sheet *a* is a stub *b*. The sheet *a* and stub *b* are divided by a scored line *c*, and the stub *b* is provided with a scored line *d* and between the lines *c* and *d* is a stub portion *e* having a strip of mucilage applied to the stub. Under each sheet *a* is a secondary sheet *a'* which is designed to receive the carbon copy of the letter or memoranda applied to the primary sheet *a*.

When it is desired to write a typewritten letter and preserve a carbon copy thereof, two sheets of the tablet are detached on the line *d* and the two sheets are placed in a typewriter with a carbon paper between them. When the letter has been written the primary sheet *a* is detached on the line *c*, to be mailed, and the carbon copy *a'* is connected to the stub *b* by moistening the mucilage on the stub portion *e* and inserting the carbon copy underneath the stub *b* and closing the book. If, for any reason, it is desired to disconnect the carbon copy from the tablet or book, it may be detached on the line *c*. When it is desired to use one of the sheets for a typewritten letter and it is desired to have a carbon copy of said letter, two sheets are detached from the tablet and a piece of carbon paper inserted between the two and they are then inserted in the typewriter and the letter is written. After the letter is written, the original copy is inclosed within the envelop to be sent away and the carbon copy is placed back in the tablet by connecting it by means of the adhesive line *e*. It is sometimes necessary to detach the carbon copy from the book for the purpose of verifying the original letter, and in this case it can be again attached to the tablet by connection to the adhesive line on the stub *b*.

It will be obvious that two, three or four carbon copies of the original data may be preserved, if desired, and they are always preserved in proper form in a tablet, so that they are readily accessible whenever desired.

To hold the carbon paper within the tablet, I have provided a spring clip made from a single length of wire comprising a larger loop 3 and a smaller loop 4, said loops being connected by a cross bar 5.

A cord or string 6 passes through the cover 1 and binding 2 at the top of the tablet so that the latter may be suspended from a nail or hook when not required for use.

2
Various changes in the details of construction may be resorted to without departing from the spirit and scope of the invention as defined in the claim.

5 What is claimed is:—

A tablet comprising a cover and a series of sheets connected to said cover, a stub connected to each sheet, said stub being permanently connected to the cover, a second 10 stub portion disposed between the first mentioned stub and the original sheet and separated from the said first mentioned stub by a line of detaching perforations, each of said sheets comprising an original and a

duplicate sheet, the duplicate sheet being 15 normally attached to said second named stub portion, a line of adhesive material on said second named stub portion, and a line of detaching perforations separating each sheet and duplicate from the second named 20 stub portion.

In testimony whereof I affix my signature in presence of two witnesses.

HOWARD FREDRIC CHISM.
